UNITED STATES PATENT OFFICE.

THOMAS E. BARNUM AND HENRY H. CUTLER, OF MILWAUKEE, WISCONSIN, ASSIGNEES TO THE CUTLER-HAMMER MFG.CO., OF MILWAUKEE, WISCONSIN, A CORPORATION OF WISCONSIN.

CONTROLLER FOR ELECTRIC MOTORS.

No. 884,002.

Specification of Letters Patent.

Patented April 7, 1908.

Application filed June 18, 1902. Serial No. 112,203.

To all whom it may concern:

Be it known, that we, THOMAS E. BARNUM and HENRY H. CUTLER, citizens of the United States, residing at Milwaukee, in the county of Milwaukee and State of Wisconsin, have invented a certain new and useful Improvement in Controllers for Electric Motors, of which the following is a full, clear, concise, and exact description, reference being had to the accompanying drawings, forming a part of this specification.

Our invention relates to controllers for electric motors and preferably to such devices used in connection with motors for operating electric elevators.

It has for its object to provide in such a device means to prevent admitting current to the motor except when all or substantially all of the starting resistance is in circuit, and also to prevent operating the motor for any length of time with any of the resistance in the circuit of the motor, that is, the resistance is used for starting only and not for regulating.

25 The invention further consists in the novel features hereinafter described and particularly pointed out in the appended claims.

In the accompanying drawings in which the same reference letters are used throughout the several views to designate like parts, Figure 1 is a plan view of the controller box showing the several devices mounted therein; Fig. 2 is a side elevation of the same, the shaft being in section on the line 2—2 of Fig. 1; Fig. 3 is an elevation of the opposite side of the box, and showing the rheostat devices; and, Fig. 4 is a diagram of the circuit connections.

The controller box, 2 is of the form shown in Figs. 1, 2 and 3, and has mounted upon the face 3 which is preferably of insulation, a series of contact segments 4 with which the sections 5 of the resistance of the rheostat are suitably connected, by means of binding posts in the usual manner. Suitable carbon brushes 6 carried by the pivoted rheostat arm 7 are adapted to engage the contact segments 4 in the movement of said pivoted arm and are yieldingly pressed against said segments by suitable springs 8 as shown. The arm 7 is pivoted at 9 and carries suitable brushes 10 to engage the contact plate 11 and connecting the arm electrically therewith. The arm 7 is provided with an upwardly extending portion or bracket 12 which carries

an insulated roller 13 shown more clearly in Fig. 1, at its upper point and upon its inner face, with which the heart shaped cam 14 engages, the said cam being rigidly mounted by means of a pin 15 upon the projecting end of the shaft 16 passing through the controller box. When the shaft 16 is rotated in either direction, the heart shaped cam 14 is likewise operated, and in this movement engages the roller 13 and lifts the arm 7 to its normal position as shown in Fig. 3. Upon the bracket 12 suitable brushes 17 engage stationary contacts for a purpose hereinafter explained, bearing segments 18 being provided for said brushes 17 when the arm 7 is out of its normal position. The arm is maintained in its raised position by means of a dog or catch 19 adapted to engage beneath a lug 20 formed upon the arm 7 by means of a small plate secured by suitable screws thereto.

The armature 21 of the magnet 22 is adapted to strike the catch or dog 19 in its upper movement when the magnet is energized thereby releasing the catch 19 to permit the arm to descend. This operation does not take place as hereinafter explained until the heart shaped cam has been removed from beneath the roller 13. A stop 23 limits the upward movement of the arm 7, while another stop 24 limits its downward movement. A suitable dash pot 25 is connected with the arm 7 by means of the rod 26 and the bracket 12 to which the rod is pivoted, the lower end of the dash pot cylinder being pivoted at 27. Suitable binding posts or clips 28, 29 and 30, as well as 31, 32, and 33 serve to connect the device in the electric circuit.

The shaft 16 is extended through the box 2 and upon the opposite end carries a reversing switch 34 which is provided with suitable brushes, preferably of the carbon type at each end adapted to suitably engage with the contact segments and rings mounted upon the opposite face of the box 2, this face being likewise of insulation. The reversing switch 34 carries brushes at a shorter end which electrically connect the inner ring 35 and the adjacent segments 36, while at the opposite or longer end, similar brushes connect the segments 36 with the ring 37, additional segments 38 and 39 are located outside of the ring 37, while suitable resting plates 40 and 41 are also mounted upon the base. Suitable binding posts are also mounted upon 110

this face of the box to connect the segments in suitable manner in the circuit. Upon the extended end of the shaft 16, that is, the end extending beyond the reversing switch 34 a suitable sprocket wheel 42 is mounted and with which the sprocket chain leading from the mechanism controlled by the operating rope or lever from the elevator car engages. The main controlling switch 43 of the apparatus is mounted upon the end of the box as shown in Figs. 1 and 2, this switch is of the ordinary solenoid type and is therefore not shown or described in detail.

Referring to Fig. 4 the operation is as follows: In the position shown in the said figure, the parts are in normal position and the elevator car as well as the motor is at rest. 44 is a main switch in the power circuit which is assumed to be closed. Under normal conditions the reversing lever stands in the position shown in full lines, and the heart shaped cam 14 is likewise in the position shown in full lines. The brushes 6 of the arm 7 normally stand upon the contact segment which is electrically connected with the starting or releasing magnet 22, the latter being connected by a conductor 45 with the first segment of the resistance 5 and is therefore in series in the starting circuit with the arm 7 and resistance 5. The series winding 46 of the motor is suitably connected at one end with a third contact from the end of the series, while its middle point is connected with the ends to the last contact and its opposite terminal is connected with the last contact of the series, the said terminal being likewise connected with one of the contacts of the solenoid switch 43, the opposite contact thereof being connected through a conductor 47 with the negative side of the power circuit through the overload magnet 48, the overload magnet 48 being adapted when actuated by an overload circuit to open the circuit through the winding of the switch 43. This switch is connected by means of a conductor 49 with the segments 38 of the reversing switch, suitable resistance lamps 50 being included in said circuit when the arm 7 is out of its normal position, but being short-circuited by the brushes 17 of the said arm 7 when in normal position. Said brushes extend from opposite sides of the lamps 50 to the contacts upon which said brushes normally rest.

55 The shunt winding 51 of the motor is connected directly between the terminals of the switch 43 and the opposite side 52 of the power circuit. The armature 53 of the motor is connected by conductors 54 and 55 with the two segments 36 of the reversing switch. The arm 7 is connected by a conductor 56 with the ring contact 35 of the reversing switch and suitable resistance lamps 57 are connected between the conductor 56 and the outer segment 39 of the reversing

switch. The opposite conductor of the power circuit 52 is connected directly with the segment 37 of the reversing switch. Assuming that the main switch 44 is closed and that the shaft 16 with its co-operating parts are in normal position, it will be seen that in order to start the motor 53 it is necessary to first close the switch 43 which controls the admission of current to the motor armature and field windings. In order to operate this switch, the shaft 16 is rotated in one direction or the other according to the direction of movement which it is desired to impart to the motor 53, the position shown in dotted lines being chosen for illustration. In this position, the point of the long arm of the switch 34 engages the contact segment 38 and completes a circuit from the negative side of the power circuit over conductor 47, through the overload magnet 48, winding of switch 43, conductor 49, around the shunt of lamps 50, to contact segment 38, the reversing switch 34, contact segment 37, and conductor 52 to the opposite side of the power circuit. Owing to the shunting of the resistance lamps 50 the switch 43 is able to operate and closes the circuit through its contacts to the motor and resistance. One of the paths of current which is now closed is through the shunt winding 51 of the motor and over conductor 58 to the opposite side of the power circuit. A second path is also completed through the series winding 46 of the motor, the resistance 5, conductor 45, releasing magnet 22, arm 7, of the rheostat, conductor 56, contact ring 35, the brushes carried upon the short arm of the switch arm 34, the left hand segment 36 of the reversing switch, conductor 55, armature 53, of the motor, conductor 54, the right hand contact segment 36, thence through to 100 the switch arm 34 to the contact segment 37 and out over the conductor 52 to the other side of the power circuit. This path completes a circuit through the armature of the motor which path includes the starting resistance 5 and the series winding of the motor, the latter enabling the motor to start under load which is a condition most frequently met with in the operation of elevators. Had it been desired to operate the 110 motor in the reverse direction, the shaft 16 would have been rotated in the reverse direction which would have completed the same circuits just described, except that the current would have passed in the reverse direction through the motor armature, thus securing the desired direction of rotation of the motor. The completion of this circuit causes the operation of the releasing magnet 22 which releases the catch or dog 19 from the starting lever, and permits the same to descend by gravity, the dash pot 25 serving to control the rapidity with which the same descends. As the arm 7 descends the resistance 5 is cut out section by section until the 120 125 130

whole is removed from the circuit, the last segments serving to cut out first a portion of the series winding of the motor, and finally all of it. When the arm 7 moves downwardly from its first position the circuit through the magnet 22 and the resistance 5 is opened so that neither the magnet nor the starting resistance 5 is injured by the continued flow of current. It will be observed that before the circuit of the switch 43 can be closed at contacts 38, 38, the heart shaped cam is moved entirely out of the way of the roller 13, carried by the lever 7 so that the arm or lever is permitted to descend as rapidly as the dash pot will permit. It is therefore impossible to keep any of the resistance 5 in the circuit long enough to be injured by the heavy current flowing. In stopping the motor the reversing switch is brought to normal position by rotating the shaft 16. In so doing, the arm 34 of the reversing switch passes off from the contact segment 38 thus opening the circuit of the switch 43 which is deenergized and breaks the circuit leading to the motor 53, whereby the same is caused to stop.

When once the switch arm 34 passes off from the segment 38 it engages the segment 39 and completes the circuit from the arm 7, over conductor 56, through the lamps 57, contact segment 39, the switch arm 34 to the contact 37 and out to conductor 52; this path being parallel to that passing through the armature 53 of the motor. By reason of this path as soon as the switch 43 is opened the "kick" due to the self induction of the shunt winding 51 of the motor is provided with an outlet or path which takes up the surge and whereby the spark and other injurious effects of the "kick" is prevented. Owing to the inclusion of the lamps 50 in the circuit of the switch 43, it is now impossible to again operate the said switch, even should the operator attempt to do so by moving the reversing switch into the operating position. In other words, it is necessary for the operator to restore the arm 7 so as to short circuit lamps 50 before the motor can be again started. This operation however, again cuts in the resistance 5 so that an unduly large current cannot be thrown upon the motor. It will therefore be seen that when the switch 43 is opened for any reason whatever, it is impossible to again operate it until the reversing switch and the arm 7 have been brought back to normal position and thereby cutting in the resistance 5 and preventing all injury to the motor thereafter.

While we have described the invention with particular reference to the specific method shown of carrying the same into practical effect, we do not wish to so confine our invention, for it is obviously capable of many changes without departing from the scope or principle thereof. For example, the

magnet 22 may be connected in series with the shunt field, or in other relation so as to be operated by the operation of switch 43.

Having described our invention what we claim as new and desire to secure by Letters Patent is:

1. In a controller, the combination with an electric motor of a resistance therefor, a device for automatically removing said resistance from the circuit of the motor, hand operated means for operating said device to insert the resistance in the motor circuit, and electrically controlled means for preventing the operation of said removing means until the hand operated means has been sufficiently operated to permit all of the resistance to be removed from the motor circuit. 80

2. In a controller, the combination with a motor, of an electrically operated switch for controlling the motor circuit, a resistance for said motor, a device for automatically removing said resistance from the motor circuit, hand operated means for operating said device to insert the resistance in the motor circuit, means to prevent the operation of said removing device until said hand operated means has been sufficiently operated to permit all of said resistance to be removed from the motor circuit, and means for operating said switch to close the motor circuit. 95

3. In a controller, the combination with an electric motor, of a resistance therefor, a device for automatically removing said resistance from the motor circuit, hand operated means for operating said device to insert the resistance in the motor circuit, electrically controlled means to prevent the operation of said removing device until said hand operated means has been operated to permit all of the resistance to be removed from the motor circuit, a switch for controlling the circuit through the motor and through said electrically controlled means, and suitable means for operating said switch. 100

4. In a controller, the combination with an electric motor, of a resistance therefor, a device for automatically removing said resistance from the motor circuit, hand operated means for operating said device to insert said resistance in the motor circuit, electrically controlled means to prevent the operation of said removing device until said hand operated means has been operated sufficiently to permit all of said resistance to be removed from the circuit, a switch for controlling the motor circuit and the circuit through said electrically controlled means, and means to prevent the starting of the motor except when all of the resistance is in circuit therewith. 115

5. In a controller, the combination with an electric motor, of a resistance therefor, an automatically actuated movable element for removing said resistance from the motor circuit, hand operated means for operating 130

said movable element to insert said resistance in the motor circuit, and an electrically controlled device for preventing the operation of said movable element until said hand operated means has been sufficiently operated to permit all of the resistance to be removed from the motor circuit.

6. In a controller, the combination with an electric motor, of a starting resistance therefor, a device for automatically removing said resistance from the motor circuit, hand operated means for operating said device to insert the resistance in the motor circuit, means to prevent the operation of said removing device until said hand operated means has been sufficiently operated to permit all of said resistance to be removed from the motor circuit, and means for controlling the speed of the motor.

20 7. In a controller, the combination with an electric motor, of a starting resistance therefor, a device for automatically removing said resistance from the motor circuit, hand operated means for operating said device to insert the resistance in the motor circuit, means to prevent the operation of said removing device until said hand operated means has been sufficiently operated to permit the removal of all of said resistance from the motor circuit, and means controlled by said removing device for controlling the speed of the motor.

8. In a controller, the combination with an electric motor, of a starting resistance therefor, a device for automatically removing said resistance from the motor circuit, hand operated means for operating said device to insert the resistance in the motor circuit, means to prevent the operation of said removing device until said hand operated means has been sufficiently operated to permit all of said resistance to be removed from the motor circuit, and means controlled by said removing device for reducing the strength of the field of the motor and thereby controlling the speed thereof.

9. In a controller, the combination with an electric motor, of a resistance therefor, a device for automatically removing said resistance from said motor in a predetermined time, electrically controlled means for permitting operation of said device, an electrical switch for starting said motor, and actuating said electrically controlled means, and a second switch for controlling the operation of the first mentioned switch.

10. In a controller, the combination with an electric motor, of a resistance therefor, a

device for automatically removing said resistance from said motor in a predetermined time, electrically controlled means for permitting operation of said device, an electrical switch for starting said motor, and actuating said electrically controlled means, a second switch for controlling the operation of the first mentioned switch, and means for preventing the starting of said motor except when said resistance is in circuit therewith.

11. In a controller, the combination with an electric motor, of a resistance therefor, an automatically actuated movable element for removing said resistance from the circuit of said motor in a predetermined time, a magnet for permitting operation of said movable element, an electrically controlled switch for starting said motor and energizing said magnet to set said movable element in operation, means for preventing the starting of the motor except when said resistance is in circuit, and means for returning said movable element to its initial position when the motor is stopped.

12. The combination of an electric motor, a device for starting the latter, mechanism for varying the resistance of the motor circuit, electrically controlled means for permitting operation of said mechanism, means adapted to prevent flow of current of sufficient strength to operate said starting device, while permitting flow of sufficient current to retain said starting device in whatever relation it may previously have occupied, and a low resistance device for causing flow of current, when said mechanism is in a high-resistance condition, of amount sufficient to operate said starting device.

13. In a controller, the combination with a motor, of an electrically operated switch for the circuit of said motor, a resistance for said motor, a device for automatically removing said resistance from the circuit of said motor in a predetermined time, means for permitting operation of said device when the motor is started, means for operating said switch to start the motor, and means to prevent the starting of the motor except when said resistance is in circuit therewith.

In witness whereof, we have hereunto subscribed our names in the presence of two witnesses.
